UNITED STATES PATENT OFFICE

SIEGFRIED GROSS, OF ESSEN, GERMANY, ASSIGNOR TO FRIED KRUPP AKTIENGESELLSCHAFT, OF ESSEN-ON-THE-RUHR, GERMANY

CONICAL SPIRAL SPRING

Application filed August 3, 1923, Serial No. 297,209, and in Germany August 29, 1927.

The invention relates to conical spiral springs and consists primarily in winding the spring with such a pitch, that all of the spring threads come at least approximately simultaneously to abut on one abutment of the spring, when the ultimate load is attained.

In order that the invention may be more easily understood, an embodiment of the new 10 conical spiral spring is illustrated in the drawing which accompanies and forms part of this specification. In this drawing

Figure 1 is an axial section through the spring, while

15 Figures 2 and 3 are elevation and top view, respectively, of the steel band intended for the manufacture of the spring.

According to the invention the spring is wound with such a pitch, that the distance of 20 each point, e. g. the point P, of the narrow surface a^1 turned toward the spring abutment B, of the steel band A forming the spring in unloaded condition, from this abutment as, e. g. α is equal to the distance this 25 point has to travel under the action of the ultimate load of the spring. This design results in the fact, that in contradistinction to the well-known conical spiral springs, in which the individual coils come successively

30 to abut on the one spring abutment upon the spring being compressed, all of the spring coils simultaneously abut on the abutment upon the ultimate load being attained, so that all of the coils take part in accumulating the 35 deformation work during the whole stroke of the spring. Besides, a linear relation exists in the present conical spiral spring between the load of the spring and its stroke, which relation is in many cases desired and does not

40 actually exist with the hitherto known conical spiral springs. Fig. 2 illustrates this relationship, wherein the spring is shown in developed form. Not until the maximum load is exerted upon the spring does the portion m coincide with a line NN' , representing one of the spring abutments. In the case when but half of the ultimate load is exerted upon the spring, the displacement of the lower edge of the spring corresponds to the 45 line PQ , wherein the point Q is equidistant

from line NN' and m . The displacement of the other portions of the spring is relatively similar, being one half of that caused when the ultimate load is exerted. When the latter is exerted, the lower edge of the spring 55 abuts substantially simultaneously upon the spring abutment to which corresponds the line NPN' .

For the manufacture of the described 60 spring steel bands may be used which are either of substantially uniform width and varying thickness or of varying width and uniform thickness or, finally, of both varying width and varying thickness. Preferably the spring is manufactured from a steel 65 band that possesses a substantially uniform width and a thickness varying in such a manner, that the coils of the spring, except its unelastic end portions, increase in thickness from the inmost coil to inclusively the outermost one. Of all conical spiral springs of 70 the same power a spring of this construction occupies the smallest space.

What I claim and desire to secure by Letters Patent, is:—

1. A conical spiral spring having a graduated cross section decreasing from its base to its tip with said graduated cross section so related to the pitch with which said spring is wound that the coils thereof abut on one 80 spring abutment at least approximately simultaneously, upon the ultimate load being exerted.

2. A conical spiral spring having a graduated cross section decreasing from its base 85 to its tip with said graduated cross section so related to the pitch with which said spring is wound that the coils thereof abut on one spring abutment at least approximately simultaneously, upon the ultimate load being 90 exerted, the pitch being such that each of said coils of said spring in loaded condition is displaced an equal fraction of the distance of said coils from the one spring abutment in the rest position, said fraction being the 95 ratio of the load applied to effect said displacement to the ultimate load.

SIEGFRIED GROSS.
